INSPECTION TOOL

Edward Kupchick, Brooklyn, N. Y., assignor to
 Bulova Watch Company, New York, N. Y., a
 corporation of New York

Application April 19, 1943, Serial No. 483,609

2 Claims. (Cl. 81—43)

This invention relates to an instrument for facilitating the inspection of small articles and relates more particularly to a device for readily and conveniently examining cylindrical watch parts such as bearings or jewels.

In the manufacture of certain instruments such as watches each part must be carefully inspected, certain watch elements such as jewels being of minute dimensions and difficult to handle. Usually these parts were inspected by holding between the jaws of a tweezer and turning the tweezer as a whole in the hand to bring the different portions of the part into convenient view. Considerable difficulty attended this procedure often resulting in failure to make a proper or complete inspection.

In accordance with the present invention a tool is provided whereby the part to be inspected may be readily picked up and rotated in the line of vision of the inspector whereby a complete and effective examination of the part is quickly and conveniently accomplished.

The invention comprises a spring-arm tweezer so constructed and arranged that a part grasped between the jaws may, by a movement of one of the jaws, be rotated forward and backward along the surfaces of the jaws thus permitting a full inspection of the part. In the case of a watch jewel the aperture or bearing is conveniently disposed in full view of the inspector and the entire surface of the bearing may be readily examined. Furthermore any variation of the cylindrical surface of the part under inspection is discernible during the rotation of the part between the jaws.

The objects and advantages of the invention will be more clearly understood by reference to the following description together with the accompanying drawing, in which

Fig. 1 is a perspective view of a tool or tweezers constructed in accordance with the present invention;

Fig. 2 is a fragmentary view of the jaws of the tool in cross-section with a part held for inspection;

Fig. 3 is a view similar to Fig. 2 but showing the jaws in different positions;

Fig. 4 is an enlarged view of the jaw ends holding a part;

Fig. 5 is a view similar to Fig. 4 but showing a part held in a different position;

Fig. 6 is a view taken on line VI—VI in Fig. 2;

Fig. 7 is a view shown on the movable parts of one of the jaws, and

Fig. 8 is a perspective view of an instrument

part as an example of the configuration of the objects requiring all-over inspection.

As shown in Fig. 1 a practical embodiment of the invention may comprise a tool 10 having jaws 11 and 12 at the ends of spring arms 13 and 14 respectively. The arms are secured together at 15 in any suitable manner to provide a common fulcrum point for the jaws.

The jaw 12 consists of two jaw-parts, a relatively stationary jaw-part 16 and a relatively movable jaw-part 17. The jaw-part 17 consists of a nose-piece 18 and a plate portion 19 having posts 20 and 21 extending through a slot 22 in jaw-part 16. The post 20 is provided with a locking head 23 and the post 21 is provided with a knurled button or thumb-piece 24. The head 23 and the button 24 extend across the slot and hold the jaw 17 in slidable relation to the arm 14. As shown more clearly in Figs. 4 and 5 the nose-piece 18 of the movable jaw is provided with an under-cut guide-slot 25 to receive an end 26 of jaw-part 16 on arm 14. The jaw-part 17 may, by means of button 24, be moved forward and backward. The post 20 is positioned to serve as a stop and prevent the end 26 from leaving the slot 25. The jaw-part 17 may be reciprocated relative to the surface 27 of the jaw 11.

It will be noted that the end 28 of the jaw 11 extends beyond the nose 18 of the jaw-part 17 when the latter is in what may be termed its retracted position ready to receive a part to be inspected. The part to be examined, such for example as a cylindrical object 29 shown in Fig. 8, is picked up when the jaws are in position as shown in Fig. 2.

The article may then be inspected and during inspection it may be rotated by a force applied to the button 24. This causes the jaw-part 17 to move to position as shown in Fig. 3 during which movement the part 29 is rotated between opposing surfaces 27 and 30 of the jaw 11 and jaw-part 17.

The jaw-part 17 may be readily reciprocated to cause a rotation of the part, first in one direction and then in the opposite direction. The part may thus be completely and effectively inspected and quickly released by the operator permitting the spring arms to separate the jaws.

One of the advantages of the present tool is in making it possible for an inspector to readily pick up a small part in the same manner as followed with the ordinary tweezer.

Thus by reason of the present invention a more positive and complete inspection of small parts

is possible with a minimum amount of effort and time.

Although a preferred embodiment of the invention is shown and described herein, it is understood that modifications may be made therein without departing from the spirit and scope of the invention as set forth in the appended claims.

What is claimed is:

1. A tool for holding a cylindrical work part for inspection comprising a pair of resilient arms normally held in spaced relation, a fixed jaw at the end of one of said arms to provide a surface to engage a work part, a second jaw positioned on the other arm comprising a plate member to provide another surface to engage said work part, said plate member having a guide slot to receive an end of said last mentioned arm, a longitudinal slot in said last mentioned arm, means extending through said longitudinal slot

for holding said plate member in slidable relation to said first mentioned jaw and a finger piece for moving said plate member to change the relative positions of said surfaces to rotate said work part.

2. A tool for holding a cylindrical work part for inspection comprising a pair of resilient arms normally held in spaced relation, a straight fixed jaw at the end of one of said arms to provide a unidirectional surface to engage a work part, a second straight jaw to provide an oppositely disposed unidirectional surface to engage said work part, means for slidably mounting said second straight jaw on the other of said arms, a finger piece for moving said second jaw relative to said fixed jaw to rotate said part through a straight path for inspection.

EDWARD KUPCHICK.
